The ornamental design for a wrist watch radio telephone, as shown and described.

DESCRIPTION

FIG. 1 is a top, front and left side perspective view of a wrist watch radio telephone showing our new design with a cover in the open position;

FIG. 2 is a bottom, rear and left side perspective view thereof;

FIG. 3 is a front elevational view thereof with the strap connector removed;

FIG. 4 is a rear elevational view thereof with the strap connector removed;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a perspective view thereof similar to FIG. 1 with the cover in the closed position.
